[57] CLAIM

The ornamental design for a tape cassette, as shown and described.

DESCRIPTION

FIG. 1 is a top plan view of a tape cassette showing our new design;

FIG. 2 is a bottom plan view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is an enlarged partial cross sectional view thereof, taken along line 7—7 of FIG. 1;

FIG. 8 is an enlarged partial cross section view thereof, taken along line 8—8 of FIG. 1;

FIG. 9 is a right side elevational view of a second embodiment of the tape cassette illustrated in FIG. 1;

FIG. 10 is a left side elevational view thereof;

FIG. 11 is a top plan view thereof; and,

FIG. 12 is a bottom plan view thereof.

The front and rear elevational views of the second embodiment are the same as the corresponding views of the first embodiment.
